UNITED STATES PATENT OFFICE.

ZACHARIAS OLSSON, OF WESTPORT, CONNECTICUT, ASSIGNOR TO JAMES K. WHETEN,
OF NEW YORK, N. Y.

SIGNAL LIGHT.

Application filed October 12, 1923. Serial No. 668,089.

To all whom it may concern:

Be it known that I, ZACHARIAS OLSSON, a subject of the King of Sweden, and a resident of Westport, county of Fairfield, State 5 of Connecticut, have invented an Improvement in Signal Lights, of which the following is a specification.

This invention relates to signal lights and with regard to its more specific features to 10 such apparatus effecting a flashing or intermittent light.

One of the objects of the invention is to provide apparatus of the above nature efficient and reliable in operation and capable 15 of meeting the requirements of practical use in a highly satisfactory manner. Another object is to provide apparatus of the above nature of simple and compact construction. Another object is to provide 20 such apparatus capable of operating economically under all conditions of use and at all times dependably. Other objects will be in part obvious or in part pointed out hereinafter.

25 The invention accordingly consists in the features of construction, combination of elements, and arrangements of parts as will be exemplified in the structure to be herein-after described and the scope of the application 30 of which will be indicated in the following claims.

In the accompanying drawings in which is shown one of the various possible embodiments of this invention:

35 Figure 1 is a vertical sectional elevation, and

Figure 2 is a plan view of the apparatus shown in Figure 1, the top portion thereof being removed.

40 Similar reference characters refer to similar parts in both views of the drawings.

Referring now to the drawings in detail with reference first particularly to Figure

45 1, there is shown an outer casing or shell 10 substantially cylindrical in form, preferably formed of sheet metal and enclosed at its upper end by a cover which is hinged thereto at one side as at 11 and has a detachable catch 12 at the opposite side. The lower end of the casing 10 is closed by a sheet metal plate member 13 supported as by an annular shoulder 14 formed by turning in the metal of the casing 10. The 55 transverse plate member 13 forms a support

for a lamp mechanism which rests thereon within the casing 10. The source of light may comprise an oil lamp and is shown as such in the drawings. The burner comprising in this instance a wick support 15 and regulating mechanism 16 therefor is mounted upon a container 17 which forms a reservoir for fuel to supply the light. Secured to the upper surface of the reservoir 17 are 60 four upstanding sheet metal walls 18 which form an inner casing about the burner 15. The top of this inner casing is closed except at the central portion by a sheet metal plate 19 and about the central opening in the member 19 rest an upstanding cylindrical 65 extension 20 open at its end. In Figure 2 the apparatus is shown with the hinged cover member, which will be later described in detail, removed and reference to this figure shows more clearly the construction of 70 the parts just described.

In each wall 18 of the inner lamp casing is provided an opening 21 substantially on a level with the flame of the burner 15. These openings 21 are provided with glass 75 coverings 22 held in place thereover as by flanges 23 one of which, as shown at 24 in Figure 2, is preferably hinged to the wall of the casing to permit convenient access to the burner therein. The walls of the outer casing 10 are provided with flanged 80 openings 25 one positioned substantially opposite each opening 21 in the inner casing. Within the openings 25 are held lenses 26 of any desired type. The lenses 26 are preferably held in position over the openings 25 in conjunction with any desired form of shade as 27 by means of annular rings 28 as is shown at the right hand side of Figure 1. The light rays from the source of light at 85 the burner 15 therefore have access through the openings 21 of the inner casing and thence directly outward through the openings 25 of the outer casing.

Considering now the construction of the 90 hinged cover member closing the top of the outer casing 10, there is provided a sloping roof member 29 the edge portion 29^a of which overhangs the wall 30 which mates with the upper edge of the casing member 10. The wall 30 beneath the overhanging edge 29^a is provided with openings 31 for the admission of air and an annular member 32 depending from the roof 29 serves 95 as a baffle to direct the air downwardly be- 100 105 110

tween the walls of the inner and outer casings as indicated by the arrows. At their lower portions the walls 18 of the inner casing are provided with openings 33 through 5 which the air is admitted from the space between the two casings to supply the light. The heated gases or products of combustion from the burner rise upwardly through the passage in the top of the inner casing provided by the cylindrical extension 20. The extension 20 thus forms substantially a chimney and the upper edge thereof rests against the inner surface of the roof member 29 which is provided with a central 10 opening surrounded by an upstanding flange 34 to permit the passage of the products of combustion or heated gases therethrough. The flange 34 is surrounded by a second cylindrical member 35 secured to the outer 15 surface of the roof 29. The top of the member 35 is closed by a cap 36 the edge 36^a of which is shaped to overhang as shown. Beneath the overhanging edge 36^a of the member 36 the member 35 is provided with 20 openings 37 permitting the passage outwardly of gases from the chimney 20.

The air for supplying the burner 15 therefore is admitted through the openings 31 adjacent the top portion of the casing 10, 25 passes downwardly between the walls of the inner and outer casings and through the openings 33 to the burner. The products of combustion pass upwardly from the burner through the chimney 20 and thence 30 outwardly through the openings 37. The overhanging edges 29^a and 36^a protect the inlet and outlet passages so that the effect 35 of wind upon the light is reduced to a minimum. Furthermore, a pre-heating effect of the air for the burner is obtained 40 during its passage downwardly between the walls of the inner and outer casings.

Secured to the lower portion of the burner 15 are a pair of upwardly extending wire members 38 which terminate part way 45 through the chimney member 20 in a cross member 39. The member 39 is provided at its center and substantially at the vertical axis of the chimney 20 with a cup-shaped depression 40 which is preferably glass-lined. This depression 40 forms a bearing 50 for a pivot point 41 which is connected by a plurality of vanes 42 with the inner wall of the upper portion of a cylindrical sleeve member 43. The sleeve member 43 extends 55 downwardly about the burner 15 and the light and is rotatably supported by the pivot-pin 41 upon the supporting arms 38. The vanes 42 are shaped to provide a propeller 60 which, actuated by the products of combustion or heated gases rising from the light, rotates the sleeve 43 upon its pivot 41. It will be seen that the sleeve 43 serves to effectively guide the gases upwardly to the 65 vanes 42 of the propeller so that the full

effect of the rising gases is obtained. The rotation of the pivot-pin 41 in its glass-lined bearing 40 is substantially nonfrictional and the freely hanging sleeve 43 is therefore readily rotated about its axis by 70 the current of ascending gases.

Substantially registering with the light from the burner 15 are provided openings 44 shown as two in number in the sleeve 43. As the sleeve is rotated therefore the openings 44 coming intermittently and successively opposite the openings 21 and 25 in the casings cause the rays of light from the light source to flash intermittently through each of the lenses 26 supported in the openings 25. In this manner a flashing light is had at each of the openings of the outer casing 10. These openings 44 are preferably provided with transparent glasses 44^a which may differ one from another in color 80 and thus give successive flashes of correspondingly changing color.

When the cover is swung back about its hinge 11 the inner mechanism, comprising the fuel container 17, the burner 15 and the inner casing 18, is removable as a unit from the outer casing 10. The parts of the light are therefore all conveniently accessible. As is shown in Figure 2 there are preferably provided in the sides of the fuel reservoir 90 17 a pair of depressions 45 registering with rods 46 secured to the inner surface of the casing 10 to prevent the fuel reservoir and the parts connected thereto from moving about within the outer casing. The light 95 throughout is sturdily constructed of sheet metal and capable of withstanding hard usage. The flashing of the light is brought about in an effective manner with simple apparatus and without the necessity of auxiliary power means. The construction throughout is one which attains many practical and useful advantages.

As many possible embodiments may be 100 made of the above invention and as many changes might be made in the embodiments above set forth, it is to be understood that all matter hereinbefore set forth is to be interpreted as illustrative and not in a limiting 105 sense.

I claim as my invention:

1. In apparatus of the class described, in combination, an outer casing having means 110 permitting passage of light rays therethrough closed at its lower end and provided with a hinged cover forming a closure at its upper end, an inner casing having means permitting the passage of light rays therethrough removably supported in said first 115 casing and having adjacent its lower end openings for the admission of air, a burner positioned within said inner casing, means for admitting air adjacent the upper portion of said outer casing, said two casings forming a passage for said air downwardly 120

125

therebetween and to said openings in the lower portion of said inner casing to supply said burner, a sleeve pivotally supported above said burner and depending freely 5 about the same, said sleeve having a plurality of openings substantially on a level with said burner for the passage of light rays therethrough and said sleeve providing a passage upwardly for products of combustion 10 from said burner, a propeller in said sleeve adapted to be driven by the rising products of combustion therein to rotate said sleeve about said burner, and a passage through said hinged cover of said outer casing 15 substantially registering with the upper end of said sleeve for the discharge of products of combustion therefrom.

2. In apparatus of the class described, in combination, a fuel container, a burner centrally positioned thereon, an inner casing of sheet metal supported upon said container extending upwardly about said burner and having in its sides a plurality of openings closed by translucent material for the passage 20 of light rays therethrough and having in its lower portion openings for the admission of air to said burner, an outer casing of sheet metal supporting said fuel container in its lower portion and extending upwardly about said inner casing and spaced therefrom to provide an air passage, said outer casing having a plurality of openings covered by translucent material and substantially registering with said openings of 25 said inner casing, a removable cover for said outer casing having openings for the admission of air to said passage between said two casings, said air being adapted to pass downwardly through said passage and thence through said openings in the bottom portion of said inner casing to supply said burner, a wire supporting frame extending upwardly from said burner, a sleeve rotatably supported by said frame and depending about said burner within said inner casing and projecting through the upper end of the latter and forming a passage for leading products of combustion upwardly, said sleeve having openings therein substantially on a level with said openings in said inner and outer casings for the passage of light rays, a propeller in the upper portion 30 of said sleeve adapted to be driven by the rising products of combustion therein to rotate said sleeve about said burner, a central opening in said removable cover substantially registering with the upper end of said sleeve for the discharge of products of combustion therefrom, a sheet metal flange extending upwardly about said last opening to guide the products of combustion upwardly and having lateral openings for the discharge thereof, and a sheet metal cap upon said flange, the edge thereof overhanging said openings to protect the burner from back draft due to wind. 35

3. In apparatus of the class described, in combination, a fuel container, a burner centrally positioned thereon, an inner casing supported upon said container and extending upwardly about said burner adapted to permit passage of light rays outwardly from said burner and having openings at its lower portion for the admission of air, an outer casing supporting said fuel container in its lower portion extending upwardly about said inner casing and spaced therefrom to provide an air passage, said outer casing being closed at the bottom and having at its upper portion means for the admission of air, said air being adapted to pass downwardly through said passage and through the openings in the lower portion of said inner casing to supply said burner, a wire supporting frame extending upwardly from said burner, a cup-shaped bearing at the upper portion of said frame, a sleeve member pivotally supported in said bearing and depending about said burner within said inner casing, said sleeve having openings therein for the passage of light rays therethrough from said burner and forming a passage for leading products of combustion upwardly, a propeller in said sleeve adapted to be driven by the rising products of combustion therein to rotate said sleeve about said burner, and means substantially registering with the upper end of said sleeve for the removal of products of combustion passing upwardly therethrough. 40

45

50

In testimony whereof, I have signed my name to this specification this 8th day of October, 1923.

ZACHARIAS OLSSON.
